UNITED STATES PATENT OFFICE.

CHARLES DAVID BONSALL AND FRANK W. WOLFF, OF PARNASSUS, PENNSYLVANIA,
ASSIGNORS TO P. H. MURPHY COMPANY, OF PARNASSUS, PENNSYLVANIA, A COR-
PORATION OF PENNSYLVANIA.

METAL CARLINE.

1,315,757.

Specification of Letters Patent. Patented Sept. 9, 1919.

Original application filed January 20, 1919, Serial No. 271,973. Divided and this application filed May 31, 1919. Serial No. 300,822.

To all whom it may concern.

Be it known that we, CHARLES DAVID BONSALL and FRANK W. WOLFF, citizens of the United States, and residents of the city 5 of Parnassus, in the county of Westmoreland and State of Pennsylvania, have invented a new and useful Improvement in Metal Carlines, of which the following is a specification.

10 This invention relates to metal carlines for car roofs and particularly to the carline brackets or end members by which the carlines are secured to the side plates of the car. This application contains subject 15 matter divided out of our pending application, filed January 20, 1919, Serial No. 271,973.

One of the principal objects of the present 20 invention is to provide a light carline-bracket which is strong enough to resist bending and twisting of the carline and which can be used for connecting carlines of different sections and lengths to the side plates of the car. Another object is a carline-bracket which is simple in construction, 25 inexpensive and easy to apply and which takes up little space.

The invention consists in the improved 30 carline-bracket and in the combinations of parts hereinafter described and claimed.

In the accompanying drawing which forms part of this specification, and wherein like numerals refer to like parts wherever they occur,

35 Figure 1 is a top plan view of the end portion of a carline and a portion of the side plate of a freight car, showing a carline-bracket embodying our invention;

Fig. 2 is a side elevation of the side plate 40 and carline-bracket showing the carline in end elevation;

Fig. 3 is a side elevation of the carline and carline-bracket, the side plate being shown in cross-section;

45 Fig. 4 is a top plan view of the portion of the side plate and the end portion of the carline showing a modified form of carline and carline-bracket;

Fig. 5 is a side elevation of the side plate 50 and carline-bracket shown in Fig. 4, the carline being shown in end elevation;

Fig. 6 is a side elevation of a carline and carline-bracket, shown in Figs. 4 and 5, the side plate being shown in cross-section;

Fig. 7 is a top plan view similar to Figs. 1 and 4 showing another modified form of carline-bracket;

Fig. 8 is a vertical cross-section taken through the earline on the line 8—8 in Fig. 6 60 7 looking toward the inner face of the side plate; and

Fig. 9 is a side elevation of the carline and carline-bracket shown in Figs. 7 and 8, the side plate being shown in cross-section.

In the accompanying drawing, our carline-bracket is shown applied to the ordinary type of wooden side plate 10 and in connection with the form of carline illustrated 70 in our pending application filed January 20, 1919, Serial No. 271,973, whose end portion 11 has an inverted channel-shaped section provided with lateral base flanges 12.

In the construction shown in Figs. 1 to 3 75 of the drawing, the end of the carline is secured to the adjacent side plate 10 by means of a channel-shaped carline-bracket 13, which straddles the top of the side plate and is secured thereto by means of horizontal bolts 14 which pass through both flanges 15 of the channel-shaped carline-bracket 13 and the side plate 10. The end of the carline projects over the side plate 80 and rests on the channel-shaped carline-bracket 13, which is split crosswise on each side of its middle from the bottom of the inner flanges to the top of the outer flange, and the metal located between the slits is bent up forming a tongue 16, which projects into the end of the channel-shaped body portion 11 of the carline and is securely riveted to the under side of the web thereof. The lateral base flanges 12 of the carline are also securely riveted to the horizontal web portion of the channel-shaped carline-bracket 13.

In the construction shown in Figs. 4 to 6, 90 an angle-shaped carline-bracket is shown with its horizontal flange 17 resting on the side plate 10 of the car and projecting inwardly past the inner face of the side plate 95.

and with its vertical flange 18 projecting downwardly outside of the side plate. The ends of the lateral base flanges 12 of the carline are bent down as at 19, and the carline-bracket and carline are secured to the side plate by means of horizontal bolts 20 which extend through the vertical flange 18 of the carline-bracket and the side plate. The horizontal flange of the carline-bracket is slit back from its inner margin on opposite sides of the center, thereby forming a tongue 21 which is riveted to the underside of the web of the channel-shaped portion 11 of the carline in a manner similar to the tongue 16 of the channel-shaped carline-bracket 13 shown in Figs. 1, 2 and 3.

In the construction shown in Figs. 7 to 9, the carline-bracket 22 is channel-shaped and straddles the top and side plate 10. The outer flange of the bracket is secured to the side plate by means of bolts 23 which extend horizontally through the side plate. The top web portion of the bracket is secured in position by means of bolts 24 which extend vertically through the side plate. The inner vertical flange of the bracket is bent inwardly horizontally, as at 25, and forms a support for the end of the carline which rests thereon and has its lateral base flanges 12 riveted securely thereto. The inner flange of the bracket is slit crosswise of the bracket on each side of the center, and the metal between the slits is bent upward in the form of a tongue 26, which is riveted to the top of the web of the channel-shaped portion 11 of the carline thereby constituting additional securing means for the ends of the same.

The carline-brackets are securely bolted or otherwise secured to the side plates; and the slitting of the brackets permits them to engage the ends of various sections of carlines and to be secured thereto across their entire end portion.

It is evident that said carline-brackets may also be used for securing carlines of various commercial shapes to the side plates of the car and that changes in the hereinbefore described carline-brackets may be made without departing from the invention as claimed.

What we claim is:

1. A carline-bracket comprising a body portion adapted to be secured to the side plate of a car, said body portion having a tongue projecting therefrom and being adapted to be secured to the bottom of the carline and a tongue being adapted to be secured to its top. 55

2. A carline-bracket comprising an inverted channel-shaped body portion adapted to straddle the side plate of a car and be secured thereto, the body portion of said carline-bracket having a tongue projecting therefrom crosswise of the channel, whereby 65 the body portion of said carline-bracket is adapted to be secured to the bottom of a carline and the tongue is adapted to be secured to its top. 60

3. A carline-bracket comprising an inverted channel-shaped body portion adapted to straddle the side plate of a car and be secured thereto and comprising inner and outer flanges, the inner flange of said carline-bracket being bent inwardly horizontally to form a support for the end of a carline which is adapted to be secured thereto, said carline-bracket having slits extending inwardly from the edge of one flange and partly across the body portion thereby forming a tongue, said tongue being adapted to be secured to the top of the carline. 75 80

4. A carline-bracket comprising a body portion adapted to rest on and be secured to the side of a car, the body portion of said carline-bracket having a tongue projecting inwardly therefrom, the body portion of said carline-bracket being adapted to be secured to the bottom of a carline and the tongue being adapted to be secured to its top. 85 90

5. A carline-bracket comprising a body portion adapted to be secured to the side plate of a car, said bracket member having slits extending inwardly from one edge 95 partly across its body portion forming a tongue, said tongue being adapted to be secured to the top of a carline.

Signed at Parnassus, Pa., this 5th day of May, 1919.

CHARLES DAVID BONSALL.
FRANK W. WOLFF.
